UNITED STATES PATENT OFFICE

CARL SCHAUM, OF PHILADELPHIA, PENNSYLVANIA, ASSIGNOR TO FLETCHER WORKS, INCORPORATED, OF PHILADELPHIA, PENNSYLVANIA, A CORPORATION OF PENNSYLVANIA

COMPENSATING DEVICE FOR LOOMS

Application filed January 8, 1929. Serial No. 330,988.

My invention relates to an improvement in looms and is particularly directed to a compensating device therefor.

In narrow fabric looms as now constructed 5 the batten straps are most taut when the shuttles are midway of their stroke due to the angularity of the straps at this instant.

It is of advantage, however, to have the straps most taut at the ends of the stroke of 10 the shuttles instead of midway of the shuttle stroke and one of the objects of the present invention is to provide such a construction.

A further object of the invention is the provision of a compensating device which 15 will produce the above-mentioned results, wherein the compensating device is so constructed and arranged that if desired the batten straps may be under practically uniform tension throughout the complete revolution of the cranks by which the batten is 20 operated. In other words my compensating device may be adjusted so that the strap tension is greatest at the ends of the stroke of the shuttles as distinguished from existing 25 constructions in which the tension is greatest when the shuttles are midway of their stroke, or as just mentioned I may so adjust the compensating device that the strap tension is practically uniform throughout 30 out the entire shuttle stroke.

The incorporation of my compensating device in a loom necessitates very little change in the existing structure.

Briefly I provide for bodily movement of 35 the idler pulleys for the batten straps, this movement being controlled and directed by my apparatus so as to allow the pulleys or idlers to oscillate in accordance with the movement of the batten. This oscillation 40 can be varied and so set originally as to produce uniform tension in the batten straps, if desired, throughout the entire range of movement of the batten, that is to say throughout the complete revolution of the cranks by 45 which the straps are moved; or, as above mentioned, the device can be so set that the straps will be under less tension midway of the shuttle stroke and under greatest tension at the ends of the shuttle stroke. If a 50 batten with a different stroke is placed in the

loom my invention provides for adjusting the stroke of the idlers to compensate for the changed angularity of the batten straps.

In the accompanying drawings I have shown only sufficient of the loom structure 55 to properly illustrate my invention, it being understood that the driving mechanism including the shuttle operating mechanism, etc., is of usual construction familiar to any one skilled in this art.

In the accompanying drawings, Fig. 1 is a 60 side elevational view of an embodiment of my invention; and

Fig. 2 is a section on the line 2—2 of Fig. 1.

Referring to the drawings in detail, 1 65 designates the loom batten its laysword pivoting at 2. 3 and 4 are the batten straps connected to a double crank 5 driven by elliptic gear 6 and eccentric gear 7. The belts 3 and 4 effect a drive of the shuttles diagrammatically shown at 8 in a well understood manner, for example, as shown in Patent No. 460,662, of October 6, 1891, or Patent No. 607,486, of July 19, 1898.

In looms as now constructed it is customary to pass the batten straps 3 and 4 about a pair of idler pulleys, and hence as the batten 1 is rocked on its pivot 2, due to the action of the cranks 5 it will be obvious that the tension in the straps 3 and 4 will vary depending upon the position of the batten 1 at any particular instant. Actually, in existing loom structures, the tension on the batten straps or belts is greatest when the shuttles 8 are midway of their stroke. As 80 pointed out above this is objectionable and is overcome by the present invention.

As distinguished from existing structures the present invention provides two pulleys 85 designated 9 and 10, respectively, these pulleys being pivotally mounted. Actually in the construction illustrated the pulleys 9 and 10 are carried in suitable bearings in arms 11 and 12 pivoted at 13 and 14. The belt or strap 4 passes about the pulley 9 while 90 the belt or strap 3 passes about the pulley 10. I have been referring to the members 3 and 4 as straps or belts, it is to be understood that this drive may be a chain if desired or any other form of flexible drive. 95

In line with the fulcrums of the idler pulleys 9 and 10 is pivoted a slotted arm 15. A convenient construction for the pivoting of the pulleys 9 and 10 as well as the arm 15 is to provide a short shaft 16, mounting the same in the standards 17 and 18, the upper ends of which provide the pivotal bearings 13 and 14 above referred to, attaching the arm 11 to one end of this shaft, the other arm 12 which is one of the supports for the pulleys 9 and 10 being attached to the other end of the shaft 16 to which other end the slotted arm 15 is also secured. As a matter of fact, if desired, the members 12 and 15 might be constructed integrally with each other.

The batten laysword as above pointed out is pivoted at 2 and on this same pivot I mount an arm or crank 19 in such fashion that crank 19 and the batten laysword which I shall designate 20 will rock as a unit about the pivot 2. This arm or crank 19 is connected by a link 21 to the slotted arm 15. The end of the link 21 is anchored in adjusted position to the slotted arm 15, but its position may be changed with respect to this arm by merely loosening the bolt 22 by which the link and slotted arm are attached to each other, and then rocking the link to a new position so as to vary the movement of the pulleys 9 and 10 as will be presently pointed out.

The operation of this arrangement is very simple and will be clearly understood from an inspection of the drawings, it being obvious that as the batten 1 is rocked the pulleys 9 and 10 will be rocked in their bearings 13 and 14 so as to compensate for variation in tension which would otherwise exist in the belts 3 and 4 due to the angularity of the batten 1, as it assumes its various positions in operation, with respect to the pulleys 9 and 10. Obviously by adjusting the link 21 in the slotted arm 15 the idler pulleys 9 and 10 may be so set as to produce any desired tension in the straps 3 and 4. That is to say if uniform tension throughout the movement of the batten 1 and hence the entire stroke of the shuttles 8 is desired the idlers 9 and 10 may be so set as to produce this uniform tension, or as pointed out above if preferable these idlers may be set to have the tension in the straps or belts 3 and 4 greatest at the ends of the strokes of the shuttles.

This arrangement is applicable not only to a loom in which the batten or beam has a constant stroke but is applicable as readily when a batten with a different stroke is put in the loom as it is merely necessary to relocate the link 21.

It will be obvious from the foregoing, therefore, that I have provided a compensating device for a shuttle motion in which the angularity of the straps 3 and 4 is compensated for by providing a construction

in which the idler pulleys about which the straps 3 and 4 are passed are given a slight reciprocating motion so that these pulleys will move backward toward the cranks 5 as the batten beats back and the shuttles move across the space, the idlers returning to their forward position as the batten beats forward.

It will be seen also that with my device I may compensate any desired amount simply by changing the setting of the device to vary the oscillation of the idlers 9 and 10.

Variations can be made in the details of construction above described without, however, departing from the spirit and scope of my invention. For instance, idlers 9 and 10 might be pulled forward with a belt or chain, the shuttle motion straps 3 and 4 pulling them backward. On the other hand the desired motion could be given the idlers through a cam, an eccentric or by a strap or cable wrapped around a drum or cam. All of these variations, however, come within the scope of my invention which broadly considered consists in providing a compensating device operating to compensate for the angularity of the batten straps 3 and 4 at the different positions of the batten 1, whereby the tension in the straps 3 and 4 may be adjusted as desired to make the strap tension practically uniform or to have these straps taut at the ends of the shuttle stroke and slack midway of the shuttle stroke, if desired.

What I claim is:—

1. In a loom comprising a shuttle motion including shuttle driving straps, a batten to which said straps are connected, and idler pulleys engaged by said straps and adapted to be moved bodily and automatically in the operation of the loom to regulate the tension in the shuttle straps.

2. In a loom comprising a shuttle motion including shuttle driving straps, a batten to which said straps are attached, and idlers for said straps, means for imparting bodily movement to said idlers, and means for regulating the amount of movement to be given said idlers whereby the tension in the shuttle driving straps is regulated.

3. In a loom having a shuttle motion comprising shuttle driving straps, a batten, an idler pulley for each strap, and a pivotal mounting for said pulleys whereby as the batten is rocked the idlers will be given a corresponding bodily movement to compensate for changing tension in the straps.

4. In a loom having a shuttle motion comprising a pair of shuttle driving straps, a batten to which the straps are connected, an idler pulley for each strap, a pivotal mounting for said pulleys and a link connection between the batten and the pulleys whereby the pulleys are moved bodily about their pivot to compensate for changing tension in the

shuttle driving straps as the batten is actuated.

5. A loom comprising a pair of shuttle driving straps, a batten to which said straps are connected, a pair of idler pulleys cooperating with said straps, a pivotal mounting for said pulleys, an arm on said pivot, a lever attached to said batten and rocking about the pivot of the batten and a link connecting said lever and said arm whereby as the batten is rocked the pulleys will be given a corresponding movement.

10 6. In a loom provided with a shuttle motion comprising shuttle driving mechanism, a batten, and bodily movable positive compensating mechanism cooperating with said shuttle driving mechanism to regulate the tension in the latter.

15 7. In a loom provided with a shuttle motion comprising shuttle driving mechanism, a batten, and bodily movable pivotally mounted positive compensating mechanism cooperating with said shuttle driving mechanism to regulate the tension in the latter.

20 25 8. In a loom provided with a shuttle motion comprising shuttle driving mechanism, a batten, and pivotally mounted positive compensating mechanism cooperating with said shuttle driving mechanism for regulating the tension in the shuttle driving mechanism, said compensating mechanism being controlled by said batten.

30 35 9. In a loom provided with a shuttle motion comprising shuttle driving mechanism, a batten and positive compensating mechanism to regulate the tension in the driving mechanism and movable about a pivot eccentric to the pivot of said batten.

40 10. In a loom a pivoted batten, a rotatable double crank, shuttle driving straps attached to said double crank and said batten, and positive means for compensating for variation in the tension of said straps during rotation of said crank and pivoting of said batten.

45 50 11. In a loom a pivoted batten, a rotatable double crank, shuttle driving straps attached to said double crank and said batten, and positive means intermediate the crank and batten and cooperating with said straps for compensating for variation in tension of said straps during rotation of said crank and pivoting of said batten.

This specification signed this 7th day of January, 1929.

55 CARL SCHAUM.
